UNITED STATES PATENT OFFICE.

ALPHA R. BEAL AND ANTON HETTEL, OF ROCHESTER, NEW YORK; SAID HETTEL
ASSIGNOR TO SAID BEAL.

HOLLOW COLUMN.

965,982.

Specification of Letters Patent. Patented Aug. 2, 1910.

Application filed January 25, 1909. Serial No. 474,181.

To all whom it may concern:

Be it known that we, ALPHA R. BEAL and ANTON HETTEL, citizens of the United States, and residents of Rochester, in the county of Monroe and State of New York, have invented certain new and useful Improvements in Hollow Columns, of which the following is a specification.

This invention relates to hollow columns, 10 and consists in the construction hereinafter set forth.

The object of the invention is to produce a built-up column that will be practically as strong as a solid column, and unaffected by 15 changes of humidity or temperature.

In the drawings:—Figure 1 is a cross-section of a part of a column constructed in accordance with this invention, in the process of assembling; Fig. 2 is a similar cross- 20 section of a column when completed; Fig. 3 is a partial view of a column, showing one-half in section and the other half in exterior elevation; Fig. 4 is an elevation of a 25 whole column, drawn on a reduced scale; and Fig. 5 is a partial cross-section, showing a modification.

The column is built of the blocks or staves 1, shown in the usual truncated form. At 30 suitable intervals, and at corresponding heights, perforations 2 are made through each block or stave, and through each set of said perforations (which are in alignment) a wire 3 is passed. Said wires are bent into circular form, and are sprung open 35 at their ends to enter the perforations 2 as aforesaid. When the full number of blocks or staves has been strung on the wires 3, the ends of the latter are overlapped through one or more of said blocks or staves, and 40 the whole structure is pressed tightly together in the usual manner. In one of the blocks or staves 1 are holes 4 (Fig. 1) counterbored to meet the perforations 2.

Soft metal or a composition, or some other 45 easily fusible metal, is introduced, in a molten or viscous condition, into the holes 4, and runs, or is forced if not sufficiently viscous to flow freely; thence around through all of the perforations 2, forming, when it 50 solidifies, a solid block or ring 5, in which is embedded the wire 3, thus rigidly connecting the blocks or staves. As the material 55 hardens, it shrinks slightly, and draws the blocks or staves very tightly together. No glue is used. The inequalities in the joints

may be filled with putty or white lead, or, if desired, the abutting faces of the blocks or staves may be covered with white lead before they are drawn together.

In the construction shown, the wires 3 60 have near their ends one or more offsets or bends 6, that serve to hold them more firmly in the material 5. It should also be noted that in this construction the connecting means are invisible, the only evidence of 65 it being the aperture 4, which may be plugged so that it becomes practically invisible. A column thus constructed can be turned and shaped in a lathe after the blocks are secured together. Fig. 1 shows 70 them before they have been shaped, and Fig. 2 after that has been done.

In the modification shown in Fig. 5, the wire 3 is represented as consisting of two parts 3^a and 3^b, that overlap within one of 75 the blocks 1^a; preferably opposite the hole 4 through which the metal is introduced. The wire 3 is separated in this way in order to allow for the expansion of the blocks. To provide for the return again of the wires 80 to their initial position on contraction, their ends are overlapped and each is passed through a plate 7 that fits and closes the transverse perforation in the block 1^a. Heads 8, 8 on the wires 3^a, 3^b, respectively, 85 prevent their being withdrawn from the plates 7, 7. Both plates are located, preferably, within the same blocks, and a spring 9 tends normally to separate them, so that when the blocks expand, the crossed ends 90 of the wires 3^a, 3^b are drawn in opposite directions and the plates on their ends are brought nearer together, against the resistance of the spring. In some articles that are made according to this invention, where 95 expansion and contraction may be considerable, it is advisable to introduce this yielding link in the wire 3.

What we claim is:

1. A connecting means for adjacent boards 100 and blocks, consisting of a metallic rod in matching perforations in adjacent boards or blocks, and a block of easily fusible metal, cast in place around said rod and filling the perforations; substantially as shown and de- 105 scribed.

2. The combination with a column comprising a series of boards or blocks that have transverse matching perforations in adjacent boards or blocks, of a metallic rod 110

in said perforations; and a block of easily fusible metal, cast in place around said rod and filling the perforations; substantially as shown and described.

5 3. The combination with a sectional column having a continuous perforation through the sections, extending transversely to their juncture, of a metallic rod, upon which said sections are threaded; and a 10 block of easily fusible metal, cast in place around said rod and filling said perforation; substantially as shown and described.

4. The combination with a sectional column having a continuous perforation 15 through the sections, extending transversely to their juncture, of a metallic rod having offset parts and adapted to enter said perforation; and a block of easily fusible metal, cast in place around the rod and filling said 20 perforation; substantially as shown and described.

5. The combination with a sectional column having a continuous perforation

through the sections, extending transversely to their juncture, of a metallic rod, upon 25 which said sections are threaded, and that has a yielding link; and a block of easily fusible metal, cast in place around said rod and filling said perforations; substantially as shown and described.

30 6. The combination with a sectional column having a continuous perforation through the sections, extending transversely to their juncture, of a metallic rod, upon which said sections are threaded, and that 35 has a yielding link consisting of a compressible spring 9 between plates 7, 7, on overlapping ends of the rod; and a block of easily fusible metal, cast in place around said rod and filling said perforations; substantially as shown and described.

ALPHA R. BEAL.
ANTON HETTEL.
